UNITED STATES PATENT OFFICE.

CALVIN R. WAID, OF BIRMINGHAM, ALABAMA.

FURNACE.

1,042,059.

Specification of Letters Patent.

Patented Oct. 22, 1912.

Application filed August 21, 1911. Serial No. 645,075.

To all whom it may concern:

Be it known that I, CALVIN R. WAID, a citizen of the United States, residing at Birmingham, in the county of Jefferson 5 and State of Alabama, have invented a new and useful Furnace, of which the following is a specification.

This invention relates to furnaces for stationary boilers and its principal object is 10 to produce practically complete combustion of products leaving the fire box, there being a novel form of bridge wall presenting an extensive surface the temperature of which is maintained at such a degree as to 15 ignite practically all combustible products passing over said surface, the heat being deflected upwardly against the boiler by said surface.

A further object is to provide the smoke 20 chamber with an arch so proportioned as to cause the gaseous products to become thoroughly commingled and to be ignited by the hot surface of the arch, prior to passing into the flues of the boiler.

25 With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

30 In the accompanying drawings the preferred form of the invention has been shown.

In said drawings:—Figure 1 is a central vertical longitudinal section through a furnace embodying the present improvements, the course of the gaseous products of combustion being indicated by arrows. Fig. 2 is a section on line A—B Fig. 1. Fig. 3 is a section on line C—D Fig. 1.

45 Referring to the figures by characters of reference 1 designates the fire box of the furnace and 2 designates the smoke chamber; said fire box being spaced from the smoke chamber by a bridge wall 3. The 50 upper face of the bridge wall is of considerable length, preferably about half as long as the boiler 4 supported above the bridge wall although it is to be understood that the parts may be of any other desired proportions. Said upper face of the bridge wall is concaved transversely and in-

clined upwardly and rearwardly, that end of the upper face nearest the fire box being located close to the grate 5 while the back end of the upper face of the bridge 60 wall is located close to the boiler 4.

The top of the smoke chamber is arched, as indicated at 6, the said arch extending to a point close to the upper flues 7 in the boiler and the curvature of the arch extending through approximately 160°. Thus, as shown in Fig. 1, an inverted pocket is formed above the horizontal plane occupied by the uppermost flues.

It is desired to construct the entire furnace of masonry, the arch 6 and the bridge wall being formed of fire brick. It will be apparent that the products of combustion, upon leaving the fire box 1, will pass rearwardly along the upper concave face of the 75 bridge wall which is heated to a high temperature and serves to ignite most of the unconsumed products passing thereover. Furthermore this inclined upper face of the bridge wall deflects the heat upwardly 80 against the bottom of the boiler 4 and is thus not only advantageous because of the increased consumption of fuel resulting from the use of the bridge wall, but also because of the fact that the heat is deflected 85 upwardly against the boiler and thus more quickly converts the water in the boiler into steam. The products of combustion, upon leaving the bridge wall, pass into the smoke chamber 2 and thence upwardly into the 90 pocket formed below the arch 6. This arch causes the combustion products to be deflected downwardly with a whirling action before passing into the flues 7 and, as the products pass along the inner surface of the 95 arch, they are heated to the point of ignition by the hot surface of the arch so that any unconsumed combustible products will here be ignited prior to the passage of the products into the flues 7. By giving the arch 100 the curvature shown and described, a thorough mixing of the combustion products takes place before said products pass into the flues, this being due to the downward deflection of the gases caused by the downwardly extending portion of the arch nearest the boiler 4. The course of the gaseous products has been indicated by arrows in Fig. 1 so that the advantages of the structure illustrated will be more clearly apparent.

It will be apparent by referring to the

drawings that the inclined upper face of the bridge wall is transversely concaved throughout its length. This results in the production of a fan-shaped flame and also produces an even distribution of heat to all parts of the boiler located above the bridge wall.

What is claimed is:

The combination with a fire box and a smoke chamber, of a bridge wall interposed between the fire box and the smoke chamber and having its upper face inclined upwardly to the smoke chamber from the fire box and to a point close to the boiler, the upper face of the bridge wall being concaved transversely throughout the length

thereof, and a boiler supported above the fire box and the bridge wall and having one end portion thereof projecting into the smoke chamber and abutting against the top of said chamber, the top of said smoke chamber being arched to form a pocket above the plane of the uppermost flues in the boiler.

In testimony that I claim the foregoing as my own, I have hereto affixed my signature in the presence of two witnesses.

CALVIN R. WAID.
